UNITED STATES PATENT OFFICE.

ALEXANDER R. WILSON, OF SPOKANE, WASHINGTON.

TYPE-SETTING MACHINE.

,136,192.

Specification of Letters Patent. Patented Apr. 20, 1915.

Application filed September 2, 1913. Serial No. 787,790.

To all whom it may concern:

Be it known that I, ALEXANDER R. WILSON, a citizen of the United States of America, residing at Spokane, in the county of Spokane and State of Washington, have invented certain new and useful Improvements in Type-Setting Machines, of which the following is a specification.

This invention pertains to type-setting machines adapted for the setting of type already cast, and being especially adapted for operation by the use of compressed air.

The general plan is to arrange the different type and letters in a system of magazines, there being a channel magazine for each letter and style of letter, to provide for the release of the type from the magazines as desired, dropping the same in the path of a shuttle, which is operated to drive the same to a predetermined position for line adjustment and then to provide for the forming of the lines upon the galley. Air driven pistons enter largely into the construction and operation of the machine, which taken together with gravity and the manipulation of the operator mainly accomplish the result desired. It is the purpose to provide simple construction, few movements and rapid operation.

While the actual construction of the machine may differ in non-essential details from the accompanying drawings, the main features are illustrated thereby wherein,

Figure 1, is a side elevation of the machine, Fig. 2, is a broken-away top plan view of the same, Fig. 3, is a sectional view taken on the line 3—3 of Fig. 2, Fig. 4, is a sectional view taken on the line 4—4 of Fig. 2, Fig. 5, is a combined broken-away top plan view and sectional view of the cylinders and valves, Fig. 6, is a sectional view taken on the line 6—6 of Fig. 2, Fig. 7, is a broken-away end view, showing means for regulating the piston governing the valves in one of the cylinders, Fig. 8, is an end view of one of the magazine channels containing the type, Fig. 9, is a broken-away side elevation of the same, Fig. 10, is a broken-away combined plan and horizontal sectional view of the front end of one of the magazines, Fig. 11, is a sectional view taken on the line 11—11 of Fig. 2, Fig. 12, is a sectional view taken on the line 12—12 of Fig. 4, Fig. 13, is a broken-away view of the end of a plate entering into the construction of the magazines, Fig. 14, is a detail view of

the actuating trigger entering into the construction of the magazines and serving to adjust the type for escapement from the magazines, and Fig. 15, is a detail view of the shuttle used to move the type from the point of escapement from the magazines to the point of line adjustment, the same being cut-away to show the manner of connection of the shoe therewith.

65

In order to avoid complicating the drawings I have shown only one type magazine channel and operation, while I have illustrated generally a key-board plan with a multiple number of keys shown thereon.

70

I have provided a frame 10 having vertical side walls 10^a and a vertical rear wall 10^b, while the top is angular, extending downwardly from the rear wall 10^b to the front wall 10^c (Fig. 1). The type magazine channels 11 occupy the positions on the platform 12 at the rear of the machine, paralleling the side walls 10^a. The walls 13 and 14 incase the magazine 11. The keys 15 for releasing the type from the magazine channels 11 are placed on the platform 16 at the front and lower end of the machine. The galley 17 occupies a transverse position on the angle of the top surface of the machine between the magazine channels 11 and 80 the key-board 16. Standing at right angles to the platform 12 and the galley 17 (Fig. 2) are walls 18, 19, 20 and 21. The type 75 22 (Fig. 8) are cast with a transverse groove 23 in one side. The path of the type 22 90 at (Fig. 2) after it leaves the ends 11^a of the channels 11 is along the wall 18 to the wall 13 at a position adjacent to and below the plate 24, thence along the walls 13 and 25 to the galley 17, the groove 23 in the type 95 22 engaging the bead 26 on the walls 13 and 25 and being slidable thereon.

Slidably adjusted to the wall 21, as at 27, is a portion having a wall 28 engaging the galley 17 and a wall 29 at right angles therewith, and it is between the walls 25 and 29 that the lines of type are formed, the same being projected into the galley 17 one line at a time by the mechanism hereinafter described. The dotted lines 28^a and 29^a indicate the position of the parts 28 and 29 when the space intervening is filled with type.

Referring now to the construction of the magazines 11, the details of which are 110 shown in Figs. 8, 9, 10, 13 and 14, the same are provided with vertical side walls 11^b

and 11^c and longitudinally arranged top and bottom walls 11^d and 11^e respectively. Pivoted to the walls 11^d and 11^e , as at 30, is a frame 31 having a portion 32 extending from and connected with the portions 31^a and 31^b , the same being about the width of one of the type 22. Extending outwardly from the portion 31^b is a portion 31^c having a beveled end 31^d . Along the inner side of the wall 11^e is a wall 33 which has a portion 33^a bent to a position at right angles with the main body thereof; at a position at the front end 11^a of the channel 11 an oblong slot 33^b is provided of a width in each of the portions 33 and 33^a equal substantially to the width of one of the type 22, the length of such slot being substantially equal to the length of one of the type 22 and of sufficient dimensions to pass one of the type 22 there-through. The normal position of the type 22 in the channel 11 is as shown in Figs. 8 and 10. The type nearest the exit end 11^a extending partially across the slot 33^b and partially to the rear of the portion 33^a with the portion 32 of the frame 31 resting against the side thereof as at 34 (Fig. 10). An inner wall 35 adjoins and parallels the wall 11^b extending forward to the part 32 of the frame 31. The type 22 is carried along the wall 18 to its position beneath the plate 24 by a shuttle 36 (Fig. 5) attached to the piston rod 37.

Attached to the shuttle 36 is a shoe 38 (Fig. 15) which is the part that actually comes in contact with the type 22 in the moving of the same. This shoe 38 is attached by means of a pin 39 extending into an opening 40 in the shuttle which bears against a coil spring 41 stationed in the opening 40 ahead of the pin. The spring 41 holds the shoe 38 normally at a distance from the end of the shuttle 36 as shown in Fig. 15, the spring being of sufficient resiliency to allow the shoe to give when it strikes the type 22 thereby causing the shoe to serve as a cushion for the type and preventing a rebounding of the same after it has been carried to the wall 13. The piston rod 37 (Fig. 5) carrying the shuttle 36 is driven forward by a pressure of air back of the piston 42, to which piston the rod 37 is attached. The air reaches the point 43 in front of the piston 42 as follows—The air enters the conduit 44 (Fig. 2) from a source of supply from which it passes through the conduit 45 to and into the cylinder 46, as at 47 (Fig. 5) to the rear of the piston 48, driving the piston 48 to a position at the head 49 of the cylinder 46 covering the exhaust port 49 and leaving a free passage for the air through the port 50 to the cylinder 51 at the point 43. When the piston 48 is covering the exhaust port 49 the piston 52 at the opposite end of the cylinder 46 is forward of the part 53 allowing the air in the

cylinder 51 to the rear of the piston 42 to pass through the same to the cylinder 46 to the rear of the piston 52, from whence it exhausts through the port 54. After the piston 42 has been driven forward carrying the shuttle 36 and the air back of the piston 80 escapes through port 113, a coil spring 55 encircling the piston rod 56 between the head 46^b of the cylinder 46 and a spool 57, made rigid to the rod 56, carries the rod 56 rearward and throws the pistons 48 and 52 attached thereto rearward closing the exhaust port 54 and opening the exhaust 49, as shown in Fig. 5 as well as opening the port 53 leaving a free passage for the air into the cylinder 51 to the rear of the piston 42 thereby providing for the return of the shuttle 36 to normal position as shown in Fig. 5.

Leading from the air conduit 44 (Fig. 12) is an air passage 58 leading into an oblong chamber 59 connecting with the transversely arranged air passages 60 in the vertical walls 61 between the rows of keys 15.

Vertical bores 62 (Fig. 4) are made in the walls 61 in which are inserted, first at the base thereof, coil springs 63, second, the keys 15 having a base 15 a being an air tight fit for the bore 62; an intermediate portion 15 b of smaller diameter than the bore 62 leaving an air space 64 between the inner wall of the bore and the same and an upper portion 15 c being an air tight fit for the bore 62 and a stem 15 d upon which is mounted the key-cap 15 e upon the upper surface of which is marked the characters corresponding with the type in the magazine 11 from which a type is drawn by the operation of the key.

Fitted to the upper end of the bores 62 are glands 65 having vertical openings 66 through the same through which the key stems 15 d glide when the keys 15 are operated.

Reaching from the air passages 60 to the bores 62 through the vertical walls 61 opposite each key 15 are ports 67 normally opposite the portions 15 b of the keys 15 substantially as shown in Fig. 4.

Reaching from the bores 62 (Fig. 4) into the vertical walls 68 are ports 69 connecting with the passages 70 leading to the ports 71 directly in front of pistons 72 slidably adjusted in the wall 73 and reaching to ports adjacent to and directly in front of the beveled ends 31^d or the frames 31 forming a part of the magazines 11. Secured to the horizontal wall 74 (Fig. 4) are springs 75 with their free ends 75 a bearing against the lugs 76 forming a part of the pistons 72. The outer end 56 a of the piston 56 (Fig. 6) is journaled into the bearing 77.

Leading from the port 71 is a passage-way 78 leading to a port 79 reaching to the end of the piston 80 having an arm 81 rig-

ly secured thereto and connected with the spool 57. Secured to the frame 10^a is a bracket 82 into which the piston 80 is slidably journaled as at 80^a. Leading from the cylinder 51 (Figs. 5 and 6) is a port 83 connected with a conduit 84 leading to an entrance chamber 85 connected with a passage-way 86 leading to a port 87 at the end of the piston 88 connected with the piston rod 89 attached to the bracket 90 which in turn is rigidly secured to the plate 24 by means of the pin 91 operating in an oblong slot 92 (Fig. 3). The piston 88 is operated in a cylinder 93 between the head 94 and the piston 88 of which is stationed a coil spring 95.

The passage-way 60^a (Fig. 3) connects with a port 96 leading into a bore 97 in which is placed a key 98 having a stem 99 with portions 100 and 101 snugly but slidably adjusted to the bore 97, leaving an air space 102 between the same within the bore 97.

Reaching from the air space 102 is a port 103 connecting with a passage-way 104 leading through ports 105 to ports 106 at the ends of the pistons 107 (Fig. 11). The pistons 107 are connected to rods 108 (Fig. 11) jointed to the plate 109 which carries brackets 110 rigidly secured thereto. The brackets 110 are rigidly secured to the vertical wall 25. Engaging the rod 108 are coil springs 111 stationed between the pistons 107 and the wall portion 112.

In the practical operation of the machine, a key 15 corresponding in connecting mechanism to the magazine carrying the character marked upon the key, is compressed, the normal position of the key 15 being as shown in Fig. 4, and the compressed position as shown in Fig. 3, thereby opening a passage-way through the bore 62 at 64 leaving a free passage of air from the source of supply through the conduit 44, the passage 58, the chamber 59, the passage 60, the ports 67 and 69 to and through the passage 70 to the port 71 directly in front of the piston 72 adjacent to the magazine 11 from which the type 22 is to be drawn. The air pressure drives the piston 72 forward causing the lug 76 forming a part of the piston 72 to strike against the beveled end 31^a of the frame 31, causing the frame 31 to swing sidewise on the pivots 30, thereby carrying the parts 82 sidewise and in front of the type 22 in the rear of the forward type, (Figs. 8, 9, 10, 13 and 14) permitting the single type at the end 11^a of the channel 11 to drop forward through the opening 33^b and downward against the wall 18 (Fig. 2) and to occupy the position indicated by 22^a in front of the shuttle 36.

Referring now to Fig. 4, the piston 72 has been driven forward a sufficient distance to connect the port 71 with the transverse port

78 (Fig. 6) allowing the air to reach the port 79 at the end of the piston 80 which drives the piston 80 and the rod 56 forward compressing the spring 55 and operating the pistons in the cylinders 46 and 51 to 70 drive forward the shuttle 36, as hereinbefore described, forcing the type 22^a (Fig. 5) to a position beneath the plate 24.

Referring now to Fig. 6, the air having reached the piston 80, it has carried the 75 same forward past the port 113 allowing the charge of air to exhaust therethrough and the coil spring 55 to return the piston 80 and the rod 56 to normal position as shown in Fig. 6. After the shuttle 36 has 80 been driven forward and returned as hereinbefore described, the air back of the piston 42 in the cylinder 51 passes through the port 83 (Fig. 5) and into and through the conduit 84 (Fig. 6) to and through the 85 chamber 85, the passage-way 86 to the port 87 adjacent to the piston 88 (Fig. 5) driving the piston 88 forward, which carries the plate 24 forward driving the type 22^a (Fig. 2) downward between the walls 13, 25, and 90 19 and 29 along the bead 26 forming the same in a line at the end of the galley 17. The charge of air having largely spent its force and the remainder of the air exhausts along the piston rod 89 to the open, and the 95 spring 95 returns the piston 88 and the plate 24 to normal position as shown in Fig. 5. The key 15 (Fig. 4) having been released the coil spring 63 returns the same to normal position as shown in Fig. 4, and the air 100 supply is cut off.

Referring again to the magazine operation shown in Figs. 8, 9, 10, 13 and 14, after the charge of air has exhausted from the port 71 at the end of the piston 72 (Fig. 4) 105 the spring 75 bearing against the lug 76, the same being a part of the piston, forces the same to normal position, as shown in Fig. 4.

The piston 72 being returned to normal 110 position, the point 31^a of the frame 31 is released and the coil spring 114 returns the frame 31 to normal position as shown in Figs. 8 and 10, when it stands at the side of the type 22 for the next release.

Referring now to the mechanism for adjusting the formed lines on the galley 17: Upon the compression of the key 98 (Fig. 3) the air space 102 connects the ports 96 and 103 allowing a free passage of air from the passage-way 60^a to reach the passage 104 from which it enters through the ports 105 to the ports 106 directly in front of the pistons 107 (Fig. 11) forcing the pistons and connected mechanism forward about 120 the width of a type 22, causing the wall 25 to move the type 22, formed in a line thereon, laterally upon the galley 17 the width of a type 22, making room for the formation 125 of another line of type along the wall 25. 130

- The piston 107 having been driven forward past the port 115, the charge of air exhausts therethrough and the coil spring 111 returns the piston 107 and connecting mechanism to normal position as shown in Figs. 2 and 11. When the key 98 (Fig. 3) is released by the operator the coil spring 116 returns the same to normal position as shown in Fig. 3.
- 10 The frame composed of parts 28 and 29 (Fig. 2) being slidable as described forms a supporting means for the lines of type 22 upon the galley 17, as to the right side thereof and the plate 25 forms a supporting means for said lines of type as to the left side thereof.
- 15 What I claim is,
1. A type-setting machine comprising a supporting frame, type-holding channels paralleling each other along the frame, means for permitting the escape of the type from the channels, such means comprising frames normally adapted to retain the lines of type, one of said frames hinged to swing clear of the type and to release the same by mechanical operation, a shuttle adapted for driving the type to a point of line formation, means for selecting and dropping the type from the channels singly in the path of the shuttle, means for operating the shuttle to drive the type and means for forming the type into lines.
2. A type-setting machine comprising a supporting frame, a galley and galley frame, type-holding channels, means for permitting the escapement of the type from the channels, a key platform supplied with a set of keys, a shuttle, a type-way from the channels to the galley including an intermediate way where the type are formed into lines, means for forming the type into lines, means for adjusting the formed lines of type upon the galley, cylinders adapted for carrying air, a conduit leading from a source of compressed air supply and connected with said cylinders to operate the escapement of the type from the channels to drop the same in the path of the shuttle, to operate the shuttle to drive the type to form the type into lines, to form the lines of type upon the galley by

the manual operation of the keys, the operation of the keys serving to direct the passage of air to the operating parts.

3. A type-setting machine comprising a supporting frame, a galley and galley frame, type-holding channels, means for permitting the escape of the type from the channels, a key-platform supplied with a set of keys, a shuttle, a type-way from the channels to the galley including an intermediate way where the type are formed into lines, means for forming the lines of type, means for adjusting the formed lines of type upon the galley, cylinders adapted for carrying air, a conduit leading from a source of compressed air supply and connected with said cylinders to operate the escapement of the type from the channels to drop the same in the path of the shuttle by the manual operation of the keys, the operation of the keys serving to direct the passage of air to the operating parts.

4. A type-setting machine comprising a supporting frame, a galley and galley frame, type-holding channels, means for permitting the escapement of the type from the channels, a key platform supplied with a set of keys, a shuttle, a type-way from the channels to the galley including an intermediate way where the type are formed into lines, means for forming the lines of type, means for adjusting the formed lines of type upon the galley, cylinders adapted for carrying air, a conduit leading from a source of compressed air supply and connected with said cylinders, to operate the escapement of the type from the channels to drop the same in the path of the shuttle to operate the shuttle to drive the type to form the type into lines by the manual operation of the keys, the operation of the keys serving to direct the passage of air to the operating parts.

In testimony whereof I have affixed my signature in presence of two witnesses.

ALEXANDER R. WILSON.
